UNITED STATES PATENT OFFICE.

DAVID C. WILLIAMS, OF CAMBRIDGE, MASSACHUSETTS.

DEVICE FOR TEACHING READING AND SENDING TELEGRAPH MESSAGES.

SPECIFICATION forming part of Letters Patent No. 769,422, dated September 6, 1904.

Application filed February 10, 1903. Serial No. 142,796. (No model.)

To all whom it may concern:

Be it known that I, DAVID C. WILLIAMS, of Cambridge, in the county of Middlesex and State of Massachusetts, have invented certain 5 new and useful Improvements in Devices to Teach Reading and Sending of Telegraph Messages, of which the following is a specification.

My invention relates to a device or game by 10 which one may reproduce the succession of sounds or taps which make up each character of the telegraph-code. I attain this by the mechanism illustrated in the accompanying drawing, in which—

15 A is a card of pasteboard or other suitable material. The edge or edges of this card are so notched that if a strip of pliable material B is drawn across the notched edge the suc-

cession of sounds or taps produced will reproduce some character of the telegraph-code. 20

What I claim as my invention, and desire to secure by Letters Patent, is—

In a card of suitable material, a combination of notches so cut and so placed on the edge or edges, that the succession of sounds 25 or taps produced by a strip of pliable material being drawn across the notched edge will reproduce some corresponding character or characters of the telegraph-code.

In testimony whereof I have affixed my signature in presence of two witnesses.

DAVID C. WILLIAMS.
